UNITED STATES PATENT OFFICE.

PETERSON H. CHERRY, OF LOS ANGELES, CALIFORNIA.

CIGARETTE-MACHINE.

1,012,123.

Specification of Letters Patent. Patented Dec. 19, 1911.

Application filed February 21, 1911. Serial No. 610,046.

To all whom it may concern:

Be it known that I, PETERSON H. CHERRY, a citizen of the United States, residing at Los Angeles, in the county of Los Angeles 5 and State of California, have invented a new and useful Cigarette-Machine, of which the following is a specification.

This invention relates to a machine for forming and filling cigarettes and it is particularly adapted for filling cigarettes with material such as medicinal agents which may present considerable adhesive quality when subjected to pressure, such quality interfering with the operation of the usual 10 machines employed for cigarette manufacture. The machine, however, is adaptable to tobacco or other fillers.

The main object of the invention is to provide a cigarette machine which is simple 20 and cheap in construction and rapid and efficient in operation.

Another object of the invention is to provide a cigarette machine which does not require any large outlay for a plant or for 25 operatives.

A further object of the invention is to provide a machine which will enable a person to perform the successive operations of rolling the wrapper, inserting the filler, and 30 discharging the cigarette from the machine, quickly and conveniently.

Other objects of the invention will appear hereinafter.

The accompanying drawings illustrate 35 the invention, and referring thereto:—Figure 1 is a plan of the machine. Fig. 2 is a vertical section on line x^2-x^2 Fig. 1. Fig. 3 is a rear elevation of the machine. Fig. 4 is an elevation of the forming and filling 40 tube, showing the manner in which the paper is rolled thereon. Fig. 5 is a longitudinal section of the cigarette forming case, and support for said case and for the filler, showing the forming and filling tube 45 in position therein. Fig. 6 is a view similar to Fig. 5, showing the engagement with the wrapper of the means for retaining the same in the case while the forming tube is being withdrawn. Fig. 7 is a vertical section 50 of the machine, showing the tube in position for filling, and the tamping device in operation. Fig. 8 is a view similar to Fig. 7, showing the manner in which the cigarette is ejected from the machine. Fig. 55 9 is a section on line x^3-x^3 Fig. 5.

The machine is supported on any suitable

base 1 formed, for example, with side portions 2 for resting on a table or other support to support the base 1 in an inclined position. Said base 1 is provided with a slot 3 extending from the front portion of said top to the center portion thereof and enlarged at the central portion to form an opening 4. The walls of the slot 3 are beveled as shown at 3'. A semi-circular seat or 60 notch 7 is formed in the base 1 at the forward end of said slot 3. Rearwardly of the opening 4 there is secured to the base 1 a case 5 which is tubular and of dimensions to fit and form the tubular wrapper of the 70 cigarette, said case being secured to the base 1 by any suitable means, for example, by staples 6. A movable closure is provided for the lower rear end of said case consisting of a plate 8 pivoted to the base 1 and 75 adapted to swing up against the rear end of the case 5 to close the same, said plate being provided at its upper end with a hook 10 adapted to snap over a projection 11 on the case to hold the said plate in closed position. A detent or stop means consisting of 80 a bar 12 is secured to the base 1 and extends obliquely inward and rearward toward the case 5, its rear end being beveled and being directly adjacent to the forward end of the 85 case 5 at one side thereof. A similar bar 13 is pivoted at 13' to the base 1 and is provided with a beveled end also extending adjacent to the forward end of the case 5. The forward upper end of the case 5 extends 90 partly over the opening 4.

A forming and filling tube 14 is provided of a diameter corresponding to the internal diameter of the cigarette tube, said tube 14 having an annular collar or shoulder 15 95 thereon at such distance from one end of the tube that when the cigarette paper is rolled on the tube, with one end in contact with said shoulder, the paper will extend at its other end somewhat beyond the end of the 100 tube. Said tube is provided in another portion thereof with a longitudinal slot or opening 16 for entry of the filler thereinto and is provided with a tapered end portion or nozzle 17 communicating with the slotted portion of the tube so that the filler may be discharged through said nozzle into the cigarette. A shoulder or collar 18 is formed on the tube adjacent to said nozzle, for the purposes hereinafter set forth. A tamper is 110 provided consisting of a rod 20 adapted to enter within the tubular member 14 and pro-

vided at one end with a handle portion such as a knob 21.

The operation is as follows: A sheet of cigarette paper, indicated at 23, is applied to 5 a cylindrical portion 24 of the tube 14 and rolled thereon, said paper abutting at one end against the collar 15 on said tube and projecting at its other end beyond the end of said tube. The paper having been thus 10 rolled in tubular shape, its edge is moistened and pressed down on the tube to secure it and form the tubular cigarette wrapper, and the projecting end portion 23' is bent or 15 folded so as to close the end of the paper tube. The tube or member 14, with the tubular cigarette wrapper thereon, is then inserted within the case 5, said case being of such size as to fit closely thereon. The engagement of the folded-in end portion 23' of 20 the paper tube with the end of the tubular member 14, and the engagement of the collar 15 on said tube 14 with the forward end of the paper tube, insures that the paper will be pushed into the case without wrinkling or 25 tearing. The closure member 8 is then swung up to closed position against the rear end of the case 5 and pushes the tube 14 with the paper wrapper, so as to move it a small distance, and the bar 13 is then caused 30 to engage with the paper wrapper 23 either by manual operation or by other means so as to retain the tubular cigarette wrapper within the case 5, and while the said wrapper is thus held the tube 14 is withdrawn 35 from within said wrapper and from the case 5 and is then reversed or turned end to end, and its other end or nozzle 17 is inserted into the open end of the wrapper 23, as shown in Fig. 7, said tube being in such 40 position that its opening or slot 16 faces upwardly. The collar or shoulder 18 engages in this position of the parts with the end of the wrapper, and the other collar 15 engages with the front of the base 1 to aid 45 in setting the tube 14 in proper position. The filler, indicated at 25, is then poured or placed on the base 1 over the opening 4 and slot 3 and over the tube 14, a portion of said 50 filler falling through the slot 16 into the interior of said tube 14, so that when the tamper 20 is inserted and pushed downwardly within said tube 14 it drives a portion of said filler into the tubular wrapper 23 the feeding operation being aided by 55 gravity on account of the rearward slope of the base and of the case 5. By repeated longitudinal reciprocating motions of the tamper, the filler is thus pushed and packed or tamped into the wrapper, the filler being 60 pushed over on top of the tube 14 from time to time, as may be required, and the tamping operation being repeated until the wrapper is sufficiently full. The closure plate 8 is 65 then released and swung down out of the way and the cigarette is then ejected by

pushing the same out of the case by means of the tamper rod 20. The slot 3 and opening 4 permit the filler to fall through the base so as to keep the space clear in front of the case 5.

70

What I claim is:—

1. A cigarette forming and filling machine comprising a base, a tubular case thereon, said case being open at both ends, a movable closure for closing one end of 75 said case, said base being provided with an opening adjacent the other end of said case and with a slot extending forwardly from said opening, a tubular member provided at one end with a paper holder adapted to receive and support a paper wrapper rolled thereonto and insertible with said paper into said case, and said member provided with an opening communicating with the interior of the tubular member, and tamping 80 means insertible and slideable within said tubular member the slot in said base having downwardly converging side walls extending at each side of the tubular member when the latter is in place and said opening in 85 the base extending below the adjacent end of the tubular case to allow the filler to pass through said slot and opening and prevent clogging in the tamping operation.

2. In a cigarette machine, a base, a case 95 mounted thereon adapted to receive and fit a paper wrapper, said case being open at both ends, a member hinged on said base and adapted to close said case at one end, a tubular member provided with a paper 100 holder portion adapted for rolling the paper thereonto and for insertion with the paper into said case, and detent means consisting of arms mounted on said base and extending obliquely forward and inward toward 105 the case and provided at their inner ends with means adapted to engage the paper when inserted in the case to retain the same in the case when the said tubular member is withdrawn from within the paper one of 110 said arms being pivotally mounted on the base, and having a handle-portion for pressing said pivoted arm toward the case.

3. In a cigarette machine, a base, a case mounted thereon and provided with closure 115 means at one end and open at the other end, said base and the case thereon being inclined downwardly toward the closure end of the case and said case being adapted to fit and receive a tubular paper wrapper, the 120 tubular member having a nozzle at one end adapted to enter the tubular paper wrapper in the case and having an opening for supplying filler to said nozzle, and tamping means movable within said tubular member 125 to force the filler from said opening into the paper in the case.

4. A cigarette machine comprising a base, a tubular case mounted thereon and provided with hinged closure means at one end, 130

detent means for holding said closure means in closed position, the other end of the case being open, said base and the case thereon being inclined downwardly toward the closure end of the case and said case being adapted to fit and receive a tubular paper wrapper, a tubular member provided with a paper holder portion adapted for rolling the paper wrapper thereonto and for insertion with the paper wrapper into said case and provided with shoulder means for determining the position of the paper wrapper, said tubular member having at its upper end a nozzle adapted to enter the tubular paper wrapper when inserted in the case, and said other end of the tubular member

having an opening for supplying filler to said nozzle, detent means mounted on the base and adapted to engage the paper wrapper when in position on the nozzle and within the tubular case, and tamping means movable within said tubular member to force the filler from said opening into the paper in the case. 20

In testimony whereof, I have hereunto set 25 my hand at Los Angeles, California, this 14th day of February, 1911.

PETERSON H. CHERRY.
